UNITED STATES PATENT OFFICE.

WALTER C. MITCHELL, OF ST. LOUIS, MISSOURI.

SMOKE CONSUMING OR CLEANING DEVICE.

Application filed March 26, 1926. Serial No. 97,598.

This invention relates to a smoke consuming and cleaning device.

An object of the invention is to provide equipment for furnaces, kilns and the like for injecting jets of dry steam into passages of the furnaces or kilns to remove the solid and combustible elements from the smoke and thereby increase the efficiency and completeness of combustion and permitting only 10 the relatively clear smoke to pass out.

Another object of the invention is to provide the efficient means herein disclosed, including equivalent variations thereof, for subjecting the smoke to jets of steam heated 15 to a high degree of heat by the heat of the furnace, or otherwise, before being injected so as to remove from the smoke the heavy products of combustion, leaving the relatively clean or clear smoke free to pass out, with 20 out bearing these objectionable elements.

Other general and specific objects will appear from the following description, reference being made to the accompanying drawings in which

25 Fig. 1 is a vertical cross section of a portion of a down-draft kiln having the invention applied thereto.

Fig. 2 is a vertical section of a portion of an up-draft kiln containing the invention.

30 Fig. 3 is a vertical longitudinal section of one of the steam heating and injecting devices.

Fig. 4 is an outer end elevation of the device shown in Fig. 3.

35 Figs. 5, 6 and 7 are vertical sectional views on the lines 5-5, 6-6 and 7-7 respectively of Fig. 3.

It will be understood from the following 40 description of the specific application of the invention shown that the invention may be applied with equal advantages to any ceramic burning kilns and also to other smoke producing furnaces. Hence in describing the present specific embodiments and uses 45 of the invention no restriction is intended.

Fig. 1 will be recognized as a cross section of a portion of a down-draft kiln in which the kiln wall 1 rises from the arch 2 above the fire box 3 and spaced from the flash wall 4. It will be understood by those skilled 50 in the art that in a kiln of this character the direction of the draft is through the fire box, upwardly in front of the flash wall 4,

and thence downwardly back of the flash wall. In accordance with the present invention the kiln wall is provided with openings 5 therethrough which enlarge or flare inwardly and open into the space between the kiln wall and the flash wall. A deflector 6 composed of fire clay or other appropriate material, is fixed across the lower side of each opening 5. The upper wall of the deflector 6 inclines upwardly from its intersection with the outer wall, as shown, in order to deflect the steam jets properly with 65 respect to the draft.

In the case of the up-draft kilns, shown in Fig. 2, the kiln walls 7 are provided with openings 8. Across the upper side of each of the openings 8 at its intersection with the inner surface of the kiln wall a deflector 9 is fixed having its lower wall inclining from intersection with its inner wall to intersection with its upper wall so as to deflect the steam jets properly. In this type of kiln it 75 will be understood that the direction of the draft is downwardly into and through the fire box.

Each injector device comprises an element including an outer wall 10 (sheet 3), an inner wall 11 enclosed within and spaced from the outer wall 10 and connected therewith by an outer wall portion 12 and an inner wall portion 13 closing the ends of the space between said inner and outer walls. 85 A horizontal partition wall 14 within the space between the inner and outer walls of the device extends from the outer end wall 12 toward the inner end wall 13 and terminates at a slight distance from said wall 13. 90 These partitions 14 are united with the outer and inner walls 10 and 11 and with the outer end wall 12 (Figs. 3, 5 and 6), so that the steam admitted into the outer end of the space below the partitions 14 must pass inwardly below said partitions to the inner end wall 13, and thence upwardly between the inner end wall 13 and the ends of the partitions 14 and outwardly through the space above the partitions 14 to the spray 100 nozzles.

A steam supply pipe 15 opens into each of the devices above described through a branch pipe 16. The branch pipes 16 are independently controlled by valves 17, one of which is in each of said branch pipes. From 105

the outer end of the space above the partitions 14 a pipe 18 leads to a nozzle 19 supported thereby and extending into each of the injector devices comprising the structure including the walls 10 and 11. The ends of the nozzles 19 are directed inwardly so that the steam passing therefrom is ejected from the open inner end of the wall 11 and is properly deflected by the deflectors 6 and 10 9 as will be understood by reference to Figs. 1 and 2. Each pipe 18 is controlled by a valve 20. As shown (Fig. 4) the pipe 15 is a line pipe and is arranged to supply steam to any desired number of injector nozzles. 15 As the injector device walls 10 and 11 are subjected to a high degree of heat it may be desirable to provide strengthening webs 21 between and connecting said walls (Figs. 3 and 5) to prevent their distortion by the 20 heat to which they are subjected.

By reference to Fig. 3 it will be seen that the nozzle 19 is spaced from the inner wall 11, leaving a slight opening through the device through which the draft passage may 25 be seen, thus enabling the operator to observe the effects of the steam upon the smoke and, by manipulation of the valves 17 and 20, to obtain best results.

From the foregoing it will be understood 30 that the operation of the device includes the admission of steam from the supply pipe 15, through the branches 16 to the respective injectors. From the branches 16 the steam passes into the outer end of the space between the walls 10 and 11 of each injector, and thence inwardly below the partition walls 14 and upwardly across the inner ends of said partitions 14 and thence outwardly through the pipe 18 and into and from the nozzle 19, and thence inwardly into contact 40 with the smoke bearing the heavy products of combustion which it is desirable to remove.

The injection of steam in substantially the 45 manner indicated serves to materially increase the draft through the kiln, thereby correspondingly increasing the efficiency and completeness of combustion. It is, of course, apparent that the degree of heat in the air 50 in the draft passage is an important factor in determining the efficiency of combustion. It is by virtue of this fact that superheated steam affords a higher degree of efficiency than is otherwise obtainable. By superheating the steam it is dried and the heat units 55 thereof increased, so that better combustion of the volatile matter is obtained. By reason of the highly efficient combustion obtained in a kiln constructed and equipped in accordance with the present invention, the smoke resulting therefrom is substantially 60 clean and clear. As already pointed out, this is due to the increased draft afforded by the injection of steam in the direction of the 65 draft as well as the more complete combus-

tion effected by the superheated steam itself. Moreover, it has been found that in practice the dense screen of steam injected into the kiln across the draft passage serves also as a filter or clarifier for eliminating from the 70 smoke all solid and combustible matter.

It has been found in practice that this invention is highly efficient in connection with brick kilns, and it is apparent that it may be used with equally satisfactory results in 75 any ceramic burning kiln without substantial alteration of the kiln structure. By proper and obvious adaptation the invention may also be used in connection with various types of furnaces. I contemplate 80 such adaptations and all uses to which the invention may be applied.

I claim:

1. In a device of the character described, the combination with a kiln having a front 85 wall and a flash wall defining therebetween a draft passage, of an injector positioned in the opening of a front wall above the fire box of the kiln and a deflector positioned in the said opening at the inner side of the 90 wall for deflecting the injected products in the direction of the draft.

2. In a device of the character described, and in combination with a kiln having a fire box, a front wall above the said fire box, 95 of an injector positioned within an opening in the said front wall and adapted to be heated by the said wall, of means for passing steam through the said injector whereby the steam is superheated, and a deflector for 100 deflecting the injected steam in the direction of the draft within the kiln.

3. The combination with a kiln having a fire box, a front wall extending above the fire box, a flash wall defining the rear wall 105 of the fire box and a draft passage between the said front wall and flash wall, of means for injecting superheated steam through the front wall and across the draft passage, said means comprising an injector positioned 110 within an opening in the front wall, said injector being in heat conducting relation with the said wall whereby the steam passing through the same is superheated, a deflector positioned within the opening in the wall at 115 the inner side thereof for deflecting the steam in the direction of the draft.

4. In a device of the character described, the combination with a kiln having a fire box, a front wall above said fire box and a 120 flash wall defining the rear wall of said fire box, said front wall and flash wall being relatively spaced to provide a draft passage therebetween, of means for injecting a dense screen of superheated steam transversely of 125 said draft passage whereby to filter the products of combustion and to remove therefrom the unburned particles, and means associated with said first mentioned means for deflecting the injected steam in the general di- 130

rection of the draft whereby to promote combustion.

5. In a device of the character described, the combination with a kiln having a fire box and a draft passage, of means for injecting a filtering screen of steam across said draft passage whereby to cleanse the smoke

issuing from said fire box by removing heavy unburned particles therefrom, means associated with said injecting means for super-heating the steam, and means for deflecting the injected steam in the general direction of the draft. 10

WALTER C. MITCHELL.
